REFRIGERANT CIRCUIT FOR AIR
CONDITIONERS

Allen Trask, Chicago, Ill., assignor to Welbilt
Stove Company, Inc., Maspeth, N. Y., a corpora-
tion of New York

Continuation of application Serial No. 179,034,
August 12, 1950. This application December 9,
1950, Serial No. 200,080

4 Claims. (Cl. 62—8)

1

This invention relates to a refrigerant circuit for air conditioners. More particularly it relates to a refrigerant circuit utilizing a spring loaded expansion valve.

This application is a continuation of my previous application, Serial No. 179,034, filed August 12, 1950, and entitled Air Conditioner Refrigerant Circuit, now abandoned.

A general object of my invention is to provide a novel and improved refrigerant circuit for air conditioners and the like of cheap and simple construction and of improved operation.

Another object is to provide a refrigerant circuit including a spring loaded expansion valve which will approximate the load responsive performance of a conventional refrigerant circuit using a thermostatic type expansion valve.

Another object is to provide a refrigerant circuit including a spring loaded expansion valve adapted for efficiently handling a wide range of variable air conditioning loads, the cost of which approximates that of a conventional refrigerant circuit using a capillary tube type refrigerant device.

Another object is to provide a refrigerant circuit wherein a fin tube type evaporator is continually provided with liquid refrigerant throughout its entire circuit or circuits.

Another object is to provide a refrigeration system circuit wherein a fin tube type condenser is continually drained of liquid refrigerant throughout its full circuit as fast as the liquid refrigerant is condensed.

Another object is to provide a refrigeration circuit of low manufacturing and assembly cost which may be dehydrated by the circulation of a dry inert gas throughout, and thus eliminate the need for baking in a high temperature oven under a vacuum as is normally required in circuits using capillary tube expansion devices.

Another object is to provide a refrigerant circuit adaptable to a small self-contained air conditioner and constructed to facilitate service, adjustments, repair, replacements, and recharging with refrigerant while in its installed position.

Another object is to provide a refrigerant circuit for small self-contained air conditioners which is adaptable for dehydrating and charging with refrigerant in a finished cabinet after final assembly, except for the attachment of removable cabinet access covers.

A further object is to provide a refrigerant circuit approximating the cost of a conventional circuit using a capillary tube refrigerant expan-

2

sion device, which is less susceptible to the ill effects of moisture and foreign matter entrained in the circuit than the conventional circuit embodying a capillary tube refrigerant expansion device.

5 A still further object is to provide a refrigerant circuit for room air conditioners approximating the cost of a conventional circuit using a capillary tube, which will accept, and function with, its full air conditioning load in a very short period of time.

Another object is to provide a refrigerant circuit for room air conditioners comprising a spring loaded expansion valve, which circuit can be checked for proper refrigerant charge by the 15 process of removing the evaporator fan blade and observing the frost-back of the evaporator and the accumulator while the system is in operation.

Room air conditioners usually employ a refrigerant circuit embodying a capillary tube refrigerant expansion device. Design engineers are 20 confronted with a choice of using a capillary tube or a thermostatic type expansion valve. It is generally conceded that the thermostatic expansion valve imparts superior performance to an air conditioner, but the capillary tube expansion device is usually selected because of its lower cost. The industry seems to be so competitive that top performance is usually compromised in favor of saving a small amount of money. Thus 25 to achieve superior air conditioner performance through the use of an expansion device and refrigerant circuit approximating the cost of a capillary tube circuit of conventional design is a valuable objective for an invention.

30 The capillary tube circuit leaves much to be desired with respect to factory assembly, performance in the field, and service repairing. The capillary tube is essentially a constant load refrigerant control device which can be fit to a given system for best performance only under one load condition, and will not give equal efficiency under loads either lighter or heavier than the compromise load under which it works best.

35 Under light loads, the evaporator is starved of refrigerant and only partly in operation. Under extra heavy loads the capillary tube restricts the refrigerant flow from the condenser excessively causing liquid refrigerant to accumulate in and fill some of the condenser, thus reducing the effective condenser area and its efficiency. Ex- 40 cessively high compressor head pressures result, and also a corresponding increase in current demand of the compressor motor. Since room 45 air conditioners often are called upon to run on

overloaded lighting circuits this excessive power demand by capillary tube systems under peak loads is a very serious defect. This invention eliminates these defects.

Another disadvantage of the capillary tube expansion device that this invention overcomes is that capillary tube refrigerant circuits have to be dehydrated by the process of baking them in a high temperature oven with a high vacuum maintained within the circuit during the baking process. This baking and vacuum process is made necessary by the fact that the small passage within the capillary tube will not pass a dry inert gas, such as nitrogen or carbon dioxide, which might otherwise be used, and which is recommended for systems embodying this invention. When dehydrating with an inert gas the compressor of the refrigeration system is used for pumping the gas through the refrigerant circuit. The exact device used must be of such gas passing capacity that it will pass the full compressor capacity without inducing an excessive head pressure. A capillary tube cannot pass the gas volume pumped by the compressor of its respective system. The expansion valve of this invention will pass inert gas in the volume pumped by its respective compressor.

The dehydrating of a refrigeration system by means of baking under a vacuum is much more expensive and time consuming than the dehydrating process carried on with an inert gas. When the baking and vacuum process is used the refrigerant circuit of an air conditioner, for example, must be completely assembled and dehydrated separately, and then installed as a unit in the final assembly involving usually a cabinet and other components. This separate dehydrating process interferes with the timing and smooth flow of a quantity production assembly line, and it precludes the possibility of a complete assembly line process, through to final assembly, and then dehydration at the end of the assembly line at the time of final testing and charging with refrigerant.

This invention permits complete assembly of a finished room air conditioner to be made, uninterrupted, on a quantity production assembly line at the end of which the dehydration process is performed with an inert gas through one flexible tube connection that is used for pressure testing, for filling with inert dehydrating gas, for drawing a vacuum, and finally for charging with refrigerant. Thus time and duplication of effort is saved by combining the above necessary processes at one location at the end of the final assembly line. The savings thus made in assembly through the use of this invention contribute toward cost reductions which bring down the cost of systems embodying this invention to substantially the same cost level of systems embodying the conventional capillary tube.

The small diameter, long passage of capillary tubes used in room air conditioning systems makes them exceptionally susceptible to blocking by foreign matter and frozen water accidentally left in the systems. In room air conditioners the capillary tubes used are several feet in length, and their internal diameter is in the range of .055 inch. Corrosion or sludge chemically generated in the system after protracted periods of operation can block the passage through a capillary tube and render the system inoperative. This invention eliminates refrigeration system breakdown from these causes.

It is common for a room air conditioner em-

bodying a capillary tube expansion device in its refrigerant circuit to require twenty (20) to thirty (30) minutes' time after the starting switch is turned on, to progressively accept the full rated load in a balanced operating condition with the evaporator normally flooded with refrigerant throughout its full length. This is a severe disadvantage that the user of an air conditioner often regrets. It is highly desirable to have room air conditioners deliver their full rated capacity of cooled air in one or two minutes after the unit has been turned on. Air conditioners embodying this invention will deliver their full rated capacity in cooled air within one or two minutes after being started.

It is generally conceded in the industry that for all practical purposes the air conditioners embodying capillary tubes in their refrigerant circuits, are not field servicable, but must be returned to the factory or to a specially equipped service depot for repairs involving the opening and/or closing, and charging of the refrigerant circuit. The cost, time delay, trouble, and correspondence involved in service work remote from the place of installation of an air conditioner, is very undesirable to everyone involved; the user, the distributor, the dealer, and the factory that produced the machine. A field servicable air conditioner is very desirable. This invention makes practical the field servicing of a hermetically sealed air conditioning system.

The quantity of refrigerant charge in a refrigerant circuit using a capillary tube cannot be checked after the machine has been put into operation. This is a serious disadvantage to a service man because the presence of a slow leak in a circuit can best be determined by the checking of the quantity of refrigerant charge, when such check is possible. This invention creates a refrigerant circuit wherein the quantity of refrigerant charge in an air conditioner can be checked by the process of removing the evaporator fan and running the unit to observe frost accumulation on the evaporator and the accumulator. With the normal charge in circuits of this invention, the evaporator will become fully frosted, and the accumulator frosted part way up from the bottom. The accumulation of less frost than this will indicate that some of the refrigerant has leaked out of the system since it left the factory. The service man can in the event of a leak, then repair it and recharge the machine with refrigerant without removing it from its installed position. This is a time saving and money saving advantage.

These and other objects and advantages of my invention will more fully appear from the following description made in connection with the accompanying drawings, wherein like reference characters refer to similar parts throughout the several views and in which:

Figure 1 is a diagrammatical view of one embodiment of my invention showing the arrangement of the various elements contained therein;

Figure 2 is a vertical sectional view of one type of expansion valve utilized in my invention;

Figure 3 is a vertical sectional view of another type of valve which may be utilized in my invention.

Figure 4 is a vertical sectional view of still another type of expansion valve which may be utilized in my invention.

One embodiment of my invention includes, as shown in Figure 1, a compressor 5 of the hermetic type having a reciprocating piston (not shown)

and adapted for compressing a refrigerant of the type known commercially as Freon. The outlet of the compressor 5 is connected for fluid communication by a conduit 6 to the inlet of an air-cooled fin tube condenser 7. A conduit 8 connects for fluid communication the outlet of the condenser 7 with the inlet of an expansion valve indicated generally as 9. The outlet of expansion valve 9 is connected by a fluid conduit 10 to the inlet of the evaporator indicated generally as 11. The evaporator is that portion of the air conditioner which absorbs the heat from the air which is to be recirculated through the room. The outlet of the evaporator 11 is connected by fluid conduit 12 to an accumulator 13 as shown in the Figure 1. A suction conduit 14 connects the upper portion of the accumulator 13 with the inlet of the compressor 5.

A portion of the conduit 8, as best shown in Figure 1, is arranged in heat exchange relationship with a portion of the conduit 14 to form a heat exchanger which has been indicated generally as 15. That portion of the conduit 8 has been indicated as 8a in Figure 1 and that portion of the conduit 14 has been indicated as 14a. In practice the heat exchange relationship between the two conduits is obtained by metallically fusing them together with solder for a relatively long length. Often the contacting portion of conduit 8a with conduit 14a is formed in the shape of a loop to confine a long contact length in a relatively small space.

The valve 8 may be any of three types shown in Figure 2, 3, and 4. Figure 2 shows a vertical sectional view of one type of expansion valve having an inlet passage 16 which leads to valve nozzle 17. At the lower end of valve nozzle 17 is a valve seat 18 which is adapted to receive a ball-pointed needle 19 which in turn is carried at the inside of the bottom of movable cup 20. The cup 20 fits outside the nozzle 17 with ample clearance to permit a fluid to pass therebetween. There is an aperture 21 formed in the side of the cup 20 which at all times establishes communication between the outlet 22 of the valve 9 and the interior of the cup 20. The cup 20 is provided with an outwardly extending flange 23 against which a coiled spring 24 abuts. As shown, the spring 24 encircles the cup 20 and pushes upwardly against the flange 23.

A pair of rods 25 have their lower ends resting on the upper surface of the flange 23 of the cup 20. These rods extend upwardly through the main body of the valve proper through apertures provided therefor. These apertures are of sufficient diameter to provide clearance around the rods 25 for free longitudinal movement thereof and for transmittal of refrigerant vapor pressure therethrough. The upper ends of rods 25 press upwardly against the lower surface of diaphragm 26. Mounted above the diaphragm 26 is a coiled spring 27 which pushes downwardly thereagainst. The tension placed upon the spring 27 may be regulated by an adjustment knob 28. The entire upper portion of the valve is protected from dust and the like by cover 29.

Figure 3 shows a valve of somewhat similar construction to that shown in Figure 2 wherein like parts are identified with like numerals. In this structure the valve needle 19 is attached to the outside of the closed end of an inverted cup 30. Rods 25 engage the closed end of cup 30 to provide mechanical contact between the under side of diaphragm 26 and cup 30 to depress needle 19 from its seat 18 against the opposite pressure

of spring 24 and the refrigerant vapor pressure under the diaphragm 26. In this structure a refrigerant, passing from valve seat 18 to valve outlet 22, is confined to pass through a restriction tube 31.

Figure 4 shows another modified form of the expansion valve structure of Figure 2 wherein similar parts are identified with like numerals. In this structure the needle 19 as attached inside the bottom of the movable cup 20 and the cup surrounds a cylindrical guide 32 for maintaining needle 19 aligned with its seat 18. The holes 33 in the cylindrical guide 32 provide a restricted passage for the refrigerant, passing from valve seat 18 to valve outlet 22.

In each of the three expansion valve structures shown there is a spring loaded metal valve engaging a valve seat, a valve outlet, and a means for restricting the flow of refrigerant between the valve seat and the valve outlet.

My commercial adaptation of my invention to room air conditioners of one horse power and less in size, are the first structures embodying my invention that have been seen, tested and investigated by engineers skilled in the art. The operation and the results obtained in the functioning of a refrigerant circuit constructed in accordance with my invention has not, up to the present time, been completely explained to the satisfaction of the engineers skilled in the art who have had the opportunity to observe and study the functioning and results of a reduction to practice. The functioning of such a circuit will be described below in accordance with what I believe to be the best probable explanation available.

I have had opportunities to carefully observe the functioning and results obtained by my invention in refrigeration testing laboratories, in room air conditioners, and I find these results highly desirable. The reasons for these results being obtained will be explained below to the best of my ability. However, it is possible that there may be error in this explanation.

In operation, compressed refrigerant vapor is pumped from the compressor 5 through conduit 6 to the condenser 7 where it is condensed to a liquid by the transfer therefrom of its latent heat to cooling air drawn through the condenser by means not shown. Liquid refrigerant from the condenser 7 flows through conduit 8 to heat exchanger 15 from whence it enters expansion valve 9.

For the purpose of this explanation, it will be considered that the expansion valve 9 is adjusted to maintain 40 lbs. refrigerant vapor pressure in the evaporator of a room air conditioner with the room air at 80 degrees dry bulb temperature and 67 degrees wet bulb temperature, a relative humidity condition of 50%, and the incoming condenser air at the dry bulb temperature of 95 degrees. These conditions will be hereinafter referred to as the "normal" load.

When the normal load is imposed on the evaporator a substantially solid stream of liquid refrigerant will flow from the condenser 7, through the heat exchanger 15, and into the expansion valve 9. The liquid when viewed through a sight glass put in conduit 8 for test purposes has very few bubbles in it, and the sub-cooling has been observed at approximately 12 degrees. It appears probable that considerably more refrigerant vapor leaves the condenser 7 than arrives at the expansion valve 9, due to condensation of the vapor within the heat exchanger. The presence of bubbles indicates that the condenser 7 is completely drained of liquid refrigerant and

its inside surface therefore is all in use in the process of condensing refrigerant from the vapor to the liquid state. It is one of the important objectives of this invention to construct a refrigerant circuit wherein the condenser is always working at full efficiency by reason of its being drained of liquid refrigerant as fast as it is condensed.

The refrigerant which is supplied to the valve 9 by the conduit 8 is conducted through the valve inlet passage 16 and into the valve nozzle 17. The flow of refrigerant between the valve seat 18 and the needle 19 is governed by a combination of the pressure existing within the evaporator 11 and the physical form of the refrigerant as it flows between the valve seat 18 and the restriction between the valve seat 18 and the valve outlet 22. As hereinbefore explained, the restriction in the valve shown in Figure 2, is the hole 21 in the cup 20, and the clearance space between cup 20 and nozzle 17. In Figure 3, the restriction is the orifice in the restrictor tube 31. In Figure 4, the restriction is made by holes 33 in cylindrical guide 32.

As the refrigerant flows from the valve seat 18 to the valve restriction, a portion of the liquid refrigerant becomes vaporized into what is known in the industry as "flash gas." This flash gas is brought about by the pressure reduction on the refrigerant as it passes the nozzle 18. The amount of flash gas produced is determined by the amount of sub-cooling in the liquid refrigerant, and the pressure on the refrigerant at the point where the flash gas occurs between the valve nozzle 18 and the valve restriction. The restriction to refrigerant flow is more effective against refrigerant with much flash gas entrained, than it is against a flow of liquid refrigerant with a minimum of flash gas. In other words, the amount of refrigerant passed by the restriction to the outlet 22 of the valve is inversely proportional to the amount of flash gas in the refrigerant. Thus the amount of flash gas, and the factors controlling the amount of flash gas in circuits involving this invention, are of major importance to the invention.

As stated above, the refrigerant flow through the valve seat 18 is partly determined by the pressure within the evaporator 11. The needle 19 is arranged to increase the valve opening upon a decrease of evaporator pressure, and to decrease the valve opening upon an increase in evaporator pressure. This is brought about by the combination of evaporator pressure upward on diaphragm 26 and the counteracting spring pressure of spring 27 downward on the diaphragm. The diaphragm movement is transmitted through rods 25 to open and close the valve seat 18 by moving the needle 19, through its pressure on flange 23 of cup 20.

A circuit of my invention may be set for the evaporator pressure, and therefore temperature, desired under normal operating conditions by putting the system under a normal load, and then adjusting the expansion valve 9 manually by adjusting the pressure on spring 27, through turning the adjusting screw 28.

It has been observed in testing a room air conditioner embodying my invention that under an increased load on the evaporator 11 due to either warmer air, increased relative humidity of the air, or both, then the pressure in the evaporator will rise substantially in proportion to the increase in load. It is my belief that this evaporator pressure, and therefore temperature, in-

crease is brought about by a decrease in the amount of flash gas between the valve seat 18 and the valve restriction under increased loads. The reduced proportion of flash gas permits more liquid refrigerant to pass the valve restriction, and thereby under the influence of the increased load, the pressure in the evaporator rises. Of course, the rising and increased pressure delivered to the underneath part of the diaphragm 26 will bring about a reduced valve opening, but it appears from the operating results, that the reduction in the amount of flash gas will increase the refrigerant flow more than the resulting small decrease in the valve opening will restrict it. In any event, increased loads result in increased refrigerant flow into the evaporator to absorb the heat load and carry it to the condensing unit.

It has also been observed in testing a room air conditioner embodying my invention, that under a decreased load on the evaporator 11 due to either cooler air, reduced relative humidity of the air, or both, then the pressure in the evaporator will fall substantially in proportion to the decrease in load. It is my belief that this evaporator pressure, and therefore temperature, reduction is brought about by an increase in the amount of flash gas between the valve seat 18 and the valve restriction under increased loads. The increased proportion of flash gas produces a foam or froth in the refrigerant to which the valve restriction offers increased restriction to flow, and thereby under the influence of the decreased load on the evaporator, the refrigerant pressure in the evaporator falls. The decreased evaporator pressure delivered to the under side of the diaphragm 26 through the clearance around rods 25, will bring about an increased valve opening, but it appears from the operating results that the increase in the amount of flash gas will decrease the refrigerant flow more than the resulting small increase in the valve opening will increase it. In other words, under evaporator load less than normal the valve restriction seems to take over refrigerant throttling control from the diaphragm action. In any event, decreased loads result in decreased flow of refrigerant to the evaporator and lower pressures and corresponding lower temperatures in the evaporator.

After the refrigerant passes through the circuit 50 or circuits of the evaporator 11, it will pass into the accumulator 13 as a combination of liquid and vaporized refrigerant. Since the final throttling control on the refrigerant is brought about by the proportion of flash gas in the refrigerant just before it encounters the valve restriction, some uncondensed vapor always leaves the condenser with the liquid refrigerant. The condenser is kept drained of liquid refrigerant by the need for some vapor in the expansion valve for contributing to the throttling action in the valve. Therefore, in my invention, all the liquid refrigerant is passed out of the condenser as fast as it is condensed, through the expansion valve 9, and into the evaporator 11.

The circuit is charged with a measured quantity of refrigerant that will under normal load be sufficient to keep the evaporator circuits supplied with liquid refrigerant and the accumulator 13 partially full of liquid refrigerant. The amount 70 of liquid refrigerant in the accumulator is a surplus for the circuit from which more or less vapor is supplied to the circuit according to load demands and variable vapor pressures elsewhere in the circuit. The accumulator 13 is constructed as 75 a liquid trap so that under no circumstances will

liquid refrigerant flow to the compressor from the evaporator.

From the accumulator 13 saturated refrigerant vapor flows through conduit 14 to heat exchanger 15 wherein heat from hot liquid refrigerant in conduit 8a is conducted through a solder bond to conduit 14a wherein the refrigerant vapor becomes superheated, and the liquid in conduit 8a becomes sub-cooled in a corresponding amount. As hereinbefore explained, some of the refrigerant vapor from the condenser passes through or into the heat exchanger 15. Condensing of a portion of this vapor will materially affect the amount of sub-cooling of the liquid refrigerant in the heat exchanger. The more latent heat of condensation given up to the suction vapor in conduit 14a, the less will be the liquid sub-cooling.

From the heat exchanger 15 the superheated refrigerant vapor flows from conduit 14a into the suction inlet of the compressor 5 wherein it is compressed to the condensing pressure required by the condenser 7, and then discharged into the condenser. This completes the refrigerant circuit.

Referring to Figure 3, in this structure of expansion valve the valve restriction responsive to the proportion of flash gas entrained in the flow of refrigerant is the restrictor tube 31, as hereinbefore explained. When this expansion valve is applied to air conditioning systems of various capacities, the internal diameter of the bore of the restrictor tube may be as follows to serve the purposes of my invention.

Tons capacity:	Restrictor orifice diam., inches
3/4-1	1/32
1-2	1/16
2-5	5/64
5-10	7/64
10-15	1/8

The variation of evaporator pressures between low and high loads may be made to range between 5 pounds and 10 pounds as desired by increasing or decreasing the restrictor bore diameter as set forth in the table above. When the fan or blower commonly used in air conditioning to circulate air over the evaporator, is stopped, while the remainder of the system is in operation, the evaporator pressures and temperature will fall below freezing temperature to cause frost to accumulate on the portions of the evaporator and accumulator which enclose liquid refrigerant. By this frosting process, the quantity of refrigerant charge in the system can be checked for proper amount.

The expansion valve 9 will pass an inert gas in this circuit in the volume pumped by the compressor. Thus in factory dehydrating an inert dry gas may be used for the purpose of dehydrating, instead of the more costly process of dehydrating in a high temperature oven under a vacuum within the circuit. Also the expansion valve of this circuit will pass foreign matter and/or ice crystals accidentally entrained within the circuit, more easily than will a capillary tube when used as a corresponding expansion device. The movement of the valve needle induced by pressure variations on the diaphragm assists in the passing of foreign matter through the valve seat.

The structure disclosed in this application is entirely new to the art and provides a number of advantages over the types of circuits known. It accomplishes the ten (10) valuable objectives enumerated in the first part of this specification.

The combination shown includes an expansion device equal in function, superior in dependability, and approximately 40% less in cost than the thermostatic expansion valve commonly used in refrigerant circuits, and in the small capacity systems it closely approximates the cost of the capillary tube expansion devices commonly used. Field service involving opening, repairing, and recharging the circuit with refrigerant is made possible. My circuit has an efficiency, sensitivity, and control approximately equal in performance to the thermostatic expansion valve but has a cost substantially less approximating the cost of circuits embodying conventional capillary tube expansion devices.

It will, of course, be understood that various changes may be made in the form, details, arrangements, and proportions of the various parts without departing from the scope of my invention.

What I claim is:

1. An air conditioner refrigerant circuit including in combination a compressor, a condenser, a heat exchanger, an expansion valve, and an evaporator interconnected conventionally in a series circuit, said expansion valve including an inlet and an outlet, a valve seat, an actuating diaphragm arranged with one of its sides subjected to refrigerant pressure on the downstream side of said valve seat tending to throttle the valve, a spring together with atmospheric pressure operative on the opposite side of said diaphragm and tending to open said valve, and a restricting refrigerant passage between said valve seat and said outlet arranged to effect pressure drop in the refrigerant passing therethrough in direct proportion to the amount of vapor refrigerant mixed with the liquid refrigerant flowing therein, whereby the pressure and temperature in said evaporator is lowered in response to an increase of refrigerant vapor passing through said restricting passage.

2. An air conditioner refrigerant circuit including in combination a compressor, a condenser, a heat exchanger, an expansion valve, and an evaporator interconnected conventionally in a series circuit, said expansion valve including an inlet and an outlet, a valve seat, an actuating diaphragm arranged with one of its sides subjected to refrigerant pressure on the downstream side of said valve seat tending to throttle the valve, a spring together with atmospheric pressure operative on the opposite side of said diaphragm and tending to open said valve, and a restricting refrigerant passage between said valve seat and said outlet arranged to effect pressure drop in the refrigerant passing therethrough in direct proportion to the amount of vapor refrigerant mixed with the liquid refrigerant flowing therein, whereby the pressure in said evaporator may be varied between high and low loads in a range between 5 pounds and 10 pounds per square inch as desired by increasing or decreasing the restriction of said restricting passage.

3. An air conditioner refrigerant circuit including in combination a compressor, a condenser, a heat exchanger, an expansion valve, and an evaporator interconnected conventionally in a series circuit, said expansion valve including an inlet and an outlet, a valve seat, an actuating diaphragm arranged with one of its sides subjected to refrigerant pressure on the downstream side of said valve seat tending to throttle the valve, a spring together with atmospheric pressure operative on the opposite side of said dia-

11

phragm and tending to open said valve, a restricting refrigerant passage between said valve seat and said outlet, and means including said restriction to effect a pressure drop in the refrigerant passing therethrough to said evaporator, whereby the refrigerant pressure and temperature in said evaporator is reduced in direct proportion to the amount of vapor refrigerant mixed with the liquid refrigerant flowing through said restricted passage resulting in a moderate rise and fall of evaporator temperature in response to a corresponding rise and fall in the temperature of air entering said evaporator.

4. An air-conditioner refrigerant circuit including in combination a compressor, a condenser, a heat exchanger, an expansion valve, and an evaporator interconnected conventionally in a series circuit, said expansion valve including an inlet and an outlet, a valve seat, an actuating diaphragm arranged with one of its sides subjected to refrigerant pressure on the downstream side of said valve seat tending to throttle the valve, a spring together with atmospheric pressure operative on the opposite side of said diaphragm and tending to open said valve, a restricting refrigerant passage between said valve seat and said outlet, and means including said restriction to

5
